UNITED STATES PATENT OFFICE.

OTTO ARONSON, OF NEW YORK, N. Y.

CABINET.

1,033,977.

Specification of Letters Patent. Patented July 30, 1912.

Application filed January 20, 1912. Serial No. 672,493.

To all whom it may concern:

Be it known that I, Otto Aronson, a citizen of Sweden, and resident of the borough of Bronx, in the county of New York and State of New York, have invented 5 certain new and useful Improvements in Cabinets, of which the following is a specification.

This invention relates to an article of furniture on the order of a smoker's cabinet or 10 sewing table or general utility cabinet.

The object is to provide a device of this kind conveniently designed for the reception 15 of the various articles of smoking or sewing paraphernalia, the various receptacles and shelves or the like being normally received within the interior or the outer confines of the cabinet, and being simultaneously movable outward and simultaneously 20 retractable, preferably under the action of a spring or its equivalent.

The object, further, is to provide a cabinet in which the outwardly movable parts will be most compactly contained when not in 25 use, so that the cabinet at such times will occupy little space, being then suitable for use as an ornamental stand or table.

In the accompanying drawings illustrating 30 the invention: Figure 1 is a partial plan section and top plan view with parts broken away, the left hand part being in section with the parts in normal or retracted position, and the right hand part being in plan with the parts in operated or projected position; Fig. 2 is a partial section on the line 2—2 of Fig. 1 with parts broken away, the parts at the left hand side being shown in normal or retracted position, and the parts at the right hand side in operated or projected position; Fig. 3 is a front view of Fig. 1, parts at the right hand side being shown projected and parts at the left hand side retracted; Fig. 4 is a partial section on the line 4 of Fig. 1 terminating at the line 45 2—2; Fig. 5 is a partial section on the line 5 of Fig. 1, terminating at the line 2—2; and Fig. 6 is a fragmentary left hand side view of Fig. 2 with parts broken away.

The body of the cabinet comprises a lower, 50 larger compartment 10 and an upper, smaller compartment 11, set centrally on the lower compartment. The body thus forms a terraced structure of attractive appearance. It may be supported on legs 34.

55 In the lower compartment is a drawer 12, slideable forward and backward through an

opening in the front wall of the compartment and guided by guides 33. In rear of the drawer 12 and centrally of the compartment 10 are slides 24 guided by undercut 60 guides 25. These slides are movable in directions opposite to each other and at right angles to the drawer 12, to which they are connected by tapes 28, anchored at 29 to the sides of the drawer and at 30 to the inner ends of the slides, the tapes passing intermediate their ends around direction-changing rollers 31 mounted on pins 35. The drawer 12 and slides 24 are operated simultaneously in outward directions by means of 65 a lever 14, pivoted at one end at 15 to a block in the lower compartment and having an operating portion or handle 16 projecting through a slot 17. The lever is connected intermediate its ends with the drawer by 70 means of a link 32, the rear end of which is pivoted to a ledge 13 projecting rearward from the drawer. Bowed springs 26, anchored at their rear ends at 27 to the compartment 10 and at their forward ends bearing 75 against the outer ends of the slides 24 are distorted when the latter are moved in outward directions and serve to retract all the movable parts to normal position contained within the body of the cabinet. A 80 spring catch 18 is anchored at 19 to a block 20 and is provided with a retaining edge 21 which automatically catches behind the lever 14 and holds the latter and the movable parts in operated position until such 85 time as it is released, either by dépressing a spring raised button 22 (see Fig. 2) or the end 36 of the catch itself projecting outward through a slot 37 in the front wall of the compartment 10. (See Fig. 3). 90

A drawer 41 is located in the lower part of the upper compartment 11, resting on the top of the compartment 10 and sliding forward and backward through an opening in the front wall of compartment 11 and between the side walls of the compartments acting as guides. This drawer is connected to the drawer 12, so as to move therewith, by means of screws 42, which pass down through the bottom of drawer 41, through 105 clearance openings in the top of compartment 10 and into the ledge 13. It will be seen that drawer 41 does not extend forward so far as drawer 12, so that access to the latter is not obstructed. 110

The slides 24 carry shelves 23 at their outer ends, these shelves being normally

received within the upper part of compartment 10 but projecting outside thereof through openings 39 when the parts are operated. These shelves may carry match-striking pads, or they may be considerably larger so as to constitute useful extensions of the top of compartment 10.

Slides 43 are located in the upper part of compartment 11, which may be separated from the lower part of the same compartment by a wall 45; and these slides are directly over the lower slides 24, with which they are connected by screws 47 extending downward through ledges 44 on slides 43, clearance slots 46 in wall 45 and clearance slots 38 in the top of the bottom compartment into the slides 24. Slides 43 have receptacles 52 formed therein, for holding new and burned matches or other articles, and it will be observed that the receptacle slides 43 do not extend so far out as the shelves 23, so that the latter are conveniently accessible. The slides 43 operate in a space between stationary compartments or trays 40, for holding cigars or other articles. A stationary top piece 49 is located over the space between these tray receptacles, being secured by screws or otherwise to ledges 50, which in turn are secured to the inner sides of the trays 40. The slides 43 with their receptacles 52 are normally located beneath this top piece, which acts as a cover for the movable receptacles. The slides 43 carry entablatures 48 at opposite sides thereof, each entablature covering one-half of one of the trays 40, when the parts are in retracted position, but uncovering the tray when the parts are projected. These entablatures together with the top piece 49 constitute the top of the compartment 11. As shown in Fig. 6 they are flush with each other. An ash receiver or receptacle 51 for other articles is mounted centrally in the stationary top piece 49; and at opposite sides of this receiver are longitudinal ribs 53, for the reception of cigars between them.

Normally all the movable parts are located inside the cabinet. To bring the parts into use, the handle of lever 14 is grasped and pulled forward, thereby directly advancing the drawer 12 and with it the drawer 41. Through the flexible connections 28, the slides 24 are forced outward in directions at right angles to these drawers and carry with them the shelves 23, and the slides 43, with the receptacles 52 and the entablatures 48. These last uncover the trays 40. When the catch 18 is released the springs return all parts to normal positions.

Having described my invention, what I desire to secure by Letters Patent and claim is:—

1. A cabinet having parts normally contained therein, guides in which said parts are movable at angles to each other outward

from different sides of the cabinet and inward into the same, a flexible tension connection between the angularly movable parts, a direction-changing guide about which said connection passes, manual operating means applied to the part at one end of the flexible connection, and an operating spring applied to the part at the other end of the flexible connection. 70

2. In a cabinet, the combination of a drawer movable out and in through one side thereof, a slide inside the cabinet movable at right angles to said drawer, means for moving the drawer and slide simultaneously in outward and inward directions, a shelf carried by said slide so as to be projected outside of the cabinet or to be retracted, and a receptacle above said slide and connected therewith so as to move outward from the cabinet and to be retracted therein, said shelf extending outward farther than said receptacle. 75

3. In a cabinet, the combination of stationary receptacles or trays, oppositely slidable entablatures forming the top of said receptacles, movable receptacles formed with said entablatures, and a stationary top-piece normally covering said movable receptacles. 90

4. In a cabinet, the combination of a body, receptacles or trays in the top part of said body, a stationary top piece between said trays, receptacles normally covered by said top piece and slidable outward therefrom, and entablatures carried at opposite sides of each slidable receptacle and each covering half of the trays when retracted, said entablatures and top piece together forming the top of said body. 95

5. In a cabinet, the combination of a casing, oppositely movable slides therein, means for moving them outward from the casing and retracting them, receptacles moved by and with said slides, a stationary top piece beneath which said receptacles are received when the said slides are retracted, stationary drawers or trays, entablatures mounted with said receptacles and covering said trays when said slides are retracted, and shelves carried by said slides at a lower level than said receptacles and entablatures. 110

6. In a cabinet, the combination of a casing, a stationary top piece materially narrower than the casing, said top piece being provided with a central receptacle having parallel retaining ribs at each side thereof, stationary drawers or trays in the upper part of the casing at opposite sides of said top piece, and oppositely slidable members carrying receptacles normally received beneath said top piece and between said trays and entablatures normally covering said trays. 120

7. In a cabinet, the combination of a casing, upper and lower drawers connected to 130

gether and movable outward from the same side of the casing to different extents, the lower drawer projecting beyond the upper, a stationary tray or drawer above the upper 5 movable drawer, both movable drawers projecting beyond the stationary drawer when moved outward, and a movable cover for said stationary drawer or tray.

8. In a cabinet, the combination of a casing, upper and lower drawers movable outward from the same side of the casing to different extents, the lower drawer projecting beyond the upper, a stationary tray or drawer above the upper movable drawer, 10 both movable drawers projecting beyond the stationary drawer when moved outward, complementary half covers for said stationary drawers or trays slidable in opposite directions and at right angles to said 15 movable drawers, and operating means and connections between the movable parts for moving them simultaneously.

9. In a cabinet, the combination of a body comprising a lower larger compartment and 20 an upper smaller compartment set centrally on the larger compartment, a slidable drawer

in the lower compartment, slides in the lower compartment movable at right angles to the drawer and oppositely to each other, flexible connections between said drawer and 30 slides, an operating lever and a retracting spring in the lower compartment, a drawer in the lower part of the upper compartment, vertical members connecting the two drawers, oppositely slidable receptacles in the 35 upper part of the upper compartment, vertical members connecting said receptacles with said slides, a stationary top piece beneath which said receptacles are normally located, stationary receptacles or trays in 40 the upper part of the upper compartment at opposite sides of the movable receptacles and stationary top piece, and entablatures carried by said movable receptacles and forming covers for said trays. 45

Signed at the borough of Manhattan in the county of New York and State of New York this 16th day of January A. D. 1912.
